What is claimed is the ornamental design for an umbrella hitch, as shown and described.

DESCRIPTION

FIG. 1 is a perspective view of an umbrella hitch, showing my new design.

FIG. 2 is a front elevational view thereof;

FIG. 3 is a rear elevational view thereof;

FIG. 4 is a left-side elevational view thereof, the right-side elevational view being a mirror image thereof; and,

FIG. 5 is a top plan view thereof; the bottom view being a mirror image thereof.

The broken lines showing a truck and umbrella post in FIG. 1 is included for the purpose of illustrating the invention in use, and form no part of the claimed design.
